Inventor:

John Zimmer

United States Patent Office.

JOHN ZIMMER, OF PITTSBURG, PENNSYLVANIA.

Letters Patent No. 78,172, dated May 19, 1868.

IMPROVEMENT IN FURNACES FOR BOILING AND PUDDLING IRON AND OTHER METALS.

The Schedule referred to in these Letters Patent and making part of the same.

TO ALL WHOM IT MAY CONCERN:

Be it known that I, JOHN ZIMMER, of the city of Pittsburgh, in the county of Allegheny, and State of Pennsylvania, have invented a new and useful Improvement in Furnaces for Boiling and Puddling Iron and other Metals; and I hereby declare that the following is a full, clear, and exact description of my invention, reference being had to the accompanying drawings, forming part of this specification, and to the letters of reference marked thereon.

The nature of my invention consists in forming the chamber or basin of puddling-furnaces with water-spaces or "bosches" therein, and so connecting said bosches with an elevated tank or reservoir, by means of supply and return-pipes, as that the same water used for keeping the basin cool may be returned to the tank, and employed continually without waste, except such as may pass off by evaporation or as steam.

To enable others to understand, make, and put in operation my invention, I will proceed to describe its construction by reference to the annexed drawings, wherein—

Figure 1 represents a longitudinal vertical section of a puddling-furnace provided with my improvements.

Figure 2 represents a transverse longitudinal section of the furnace and basin.

Figure 3 is a front elevation of the furnace, showing the pipes and end view of the water-tank or reservoir.

All the parts are lettered, and similar letters indicate like parts in the several views.

In most puddling-furnaces heretofore constructed, the basin or chamber, wherein the metal is brought to its proper condition for working, is a mere cast-iron shell, lined with fire-brick, or other refractory substance, inlaid with pulverized iron ore, German clay, and water, incorporated with other ingredients, and denominated "fix," to enable it to withstand the intense heat to which it must necessarily be subjected; and as all this requires constant attention, continual repair, attended with loss of time, and, as a consequence, money, I have attempted, and my invention is designed, to obviate these disadvantages. With this view, I construct my furnace in any of the well-known forms, and with the usual appliances and appendages incident to such furnaces. But, in order to overcome the difficulties hereinbefore mentioned, I make the basin or puddling-chamber C of cast iron; and of one or more pieces, the sides, S, of which are cast with a hollow space or water "bosh," B, therein, and extending along the centre of each casting, in the manner indicated by the dotted lines in fig. 2, the ends being closed to prevent leakage of water or steam, at the upper side; and near the end of each piece, and communicating with the interior or bosh B, is a round hole or opening, X, to each of which I attach an upright pipe long enough to reach a short distance above the top, A, of the furnace, and where they all terminate in a large water-tank, F. The pipes, L, at one end of each bosh, B, just pass through the bottom of this tank, while the other pipes, D, extend up the outside, their upper ends being turned down a short distance to form a spout, so as to empty into the tank from above, as seen at fig. 3.

The operation is as follows: Water being placed in the tank F, it will flow down the short pipes L, and fill the space or bosh B in the cast-iron sides of the puddling-chamber C, when, on a fire being started in the furnace, the heat will soon be sufficient to generate steam in the bosh, and the pressure will, as it increases, cause the water to pass up the long pipes D and discharge into the tank F above the furnace, and, at the same time, the water in the tank will rush down the short pipes L into the bosh B, to take the place of that discharged, thus keeping up a perfect and continuous circulation of water around the puddling-chamber, and maintaining the sides S at a proper temperature, so as to avoid the troubles and difficulties so common in all puddling-furnaces constructed and worked in the ordinary manner.

Having thus briefly stated the nature of my invention—

I claim a cast-iron puddling-basin or chamber, having a bosh or water-space cast therein around its sides, in combination with an elevated water-tank, and communicating with each other by means of supply and outlet-pipes, the whole being constructed, arranged, and operating substantially as and for the purposes herein set forth;

JOHN ZIMMER.
